UNITED STATES PATENT OFFICE.

JAMES DONOVAN, OF THREE RIVERS, MICHIGAN.

WHEEL.

SPECIFICATION forming part of Letters Patent No. 636,958, dated November 14, 1899.

Application filed April 24, 1899. Serial No. 714,253. (No model.)

To all whom it may concern:

Be it known that I, JAMES DONOVAN, a citizen of the United States, residing at Three Rivers, in the county of St. Joseph and State 5 of Michigan, have invented certain new and useful Improvements in Wheels, of which the following is a specification, reference being had therein to the accompanying drawings.

The invention relates to the construction 10 of a wheel; and the invention consists particularly in the formation of the body of the wheel, whereby the rim is braced by portions of the body extending in bracing relation to the rim.

The invention further consists in the construction 15 of the hub and in the construction, arrangement, and combination of the various parts, as more fully hereinafter described, and pointed out in the claims.

I have shown the wheel as made from a single disk of metal, as illustrating what I consider the best form of my invention, and such 20 illustrations are as follows:

Figure 1 represents the disk from which the complete wheel may be made, and Figs. 2 and 25 3 are diagram-sections through the blank in process of formation. Fig. 4 is an elevation of the web of the wheel as shown in Fig. 3, showing the lines upon which the braces and spokes are formed. Figs. 5 and 6 are diagram-sections through the blank, showing the 30 final steps in forming the body of the wheel. Fig. 7 is an enlarged section through the hub portion of the wheel, showing the two sections of the hub before being secured together. Fig. 8 is a section through the hub 35 in its completed form. Fig. 9 is a sectional perspective view of the wheel to illustrate this construction. Fig. 10 is a plan view of the wheel with a portion of the rim broken 40 away to illustrate the construction of the spokes. Fig. 11 is a view similar to Fig. 10 of a slightly-modified form of brace.

While I have shown and will describe my wheel as made from a single sheet of metal, 45 I do not desire to be limited to that kind of wheel, as my invention relates more particularly to the construction of the web or body portion of the wheel regardless of whether it is made integral with the rim or not.

50 In making my wheel of a single disk I preferably proceed as follows: I take the blank shown in Fig. 1, which is a circular disk of

sheet metal, and bend it upon the dotted line lettered *a*, first, preferably, perforating it in the center, as at *b*, to act as a centering 55 means for the wheel in its further operations. The blank is preferably bent by steps upon the line *a* first into the shape indicated by the dotted lines *c* in Fig. 2 and then into the position indicated by full lines in that figure, 60 the body portion being slightly dished, as shown therein. If I desire to have a cylindrical exterior or rim, the rim may be bent into that shape; but in making a car-wheel after getting the blank into the shape shown 65 in Fig. 2 I next may shape the rim into the shape shown in Fig. 3, with the flange *e* thereon. It has heretofore been the practice to make light car-wheels, substantially as hereinbefore described, of a single sheet of 70 metal, the wheel when completed being substantially as shown in Fig. 3. This wheel comprises the rim *A* and the body or web *B*. In the use of such wheels it has been found that the overhanging rim being secured to 75 the web only on one side is very apt to break off at the bend or elbow *h*, and my invention overcomes this difficulty, besides greatly strengthening the wheel itself. I next form the separated spokes *C* by cutting the blank, 80 as shown in full lines *i k* in Fig. 4, and turning the flanges thus formed by the cuts within the tread, as shown in Fig. 5. This flange or brace *D* may then be moved into contact with the inner face of the rim by further dishing 85 of the wheel, as shown in Fig. 6. Any suitable hub may then be put upon the wheel and the wheel will be complete. The hub which I prefer I show in Figs. 7 and 8, and it consists of the plate *E*, adapted to fit upon one side 90 of the central portion of the web, and a corresponding plate *F*, adapted to fit upon the other side. This plate *F* has a spindle or skein *G*, preferably formed integral therewith, and this spindle may be forced through 95 the central portion of the web, and thereby turn up a circular flange *H* at the inner edge of the web, forming what I call a "hub-flange." This flange if thus formed will tightly embrace the spindle *G* and will be 100 forced tightly within the bore through the plate *E*, and the whole may then be clamped together by a nut *I*, engaging upon the screw-thread upon the end of the skein *G*, as plainly

shown in Fig. 8. This construction of hub saves any riveting and also gives a wide bearing by the hub-flange H upon the hub to resist the strains to which the wheel may be subjected. I may and preferably do form the brace D with a shoulder *l* at its inner end, which abuts against a shoulder upon the hub. This gives the brace D a shouldered bearing at opposite ends upon the hub and the rim of the wheel. The wheel thus constructed will be substantially as shown in Fig. 9, and it will be seen that each spoke is in effect an angle-bar comprising one member which connects the hub and the rim and a brace which extends out within the rim, forming, respectively, the parts C and D, shaped from the web.

It is evident that the form may be considerably varied and still come within my invention. For instance, the body and web of the wheel may be made in one piece and the rim in another piece secured thereto in any suitable manner, or the shape and form of the brace may be materially varied—as, for instance, in Fig. 11 I have shown a construction in which instead of cutting out the brace and turning it at an angle within the hub I simply cut the web at the edge and then bend in the material in line with the cut in the shape of a corrugation, as shown at I' in that figure, leaving the spokes C as before.

While I have shown my wheel as a car-wheel, it is evident that it may be made with a plain rim for any purpose for which it is adapted, or various other modifications may be made in it without departing from the spirit of my invention.

What I claim as my invention is—

1. In a wheel, the combination of the rim, the body formed of a sheet-metal web comprising spokes and braces formed of portions of the web between the spokes, extending into bracing relation to the inner face of the rim.
2. In a wheel the combination of a rim, a hub, a body formed of a sheet-metal web, dished, and having integral radial spokes formed therefrom, and braces formed of the integral portions of the web between the spokes bent within the rim to brace the same.

3. In a wheel, the combination of the rim, 50 the hub, a body formed of a sheet-metal web shaped to form angle-bar spokes one member of each spoke connecting the rim to the hub and the other member extending within and bracing the rim.

4. A sheet-metal wheel formed from a single blank shaped into a web and a tread formed by turning outward the edge of the blank; and braces for the tread formed by integral portions of the web extending from the web portion within and in contact with the inner face of the tread. 60

5. A sheet-metal wheel formed from a single blank shaped into a web, and a rim formed by turning over the edge of the blank, braces 65 for the rim formed by integral portions of the web struck out under the rim, the wheel being dished to bring the braces into contact with the inner face of the rim.

6. In a wheel, the combination of the rim, 70 of a body formed of sheet metal with a hub-flange at its center concentric with the rim, and a hub, comprising a flanged thimble engaging within the hub-flange, and a plate engaging over the hub-flange on the other side, 75 and a nut on the end of the thimble for clamping the web between the flange of the thimble and the plate.

7. In a wheel, the combination of a rim, a hub, a body or web of sheet metal, spokes 80 connecting the hub and the rim, braces struck out between the spokes and turned within the hub, such braces having shouldered engagement at opposite ends with the rim and hub respectively.

8. A sheet-metal wheel formed from a single blank shaped into a web, and a tread formed by turning over the edge of the blank, the web being formed into spokes, and braces 90 extending from the spokes to the inner face of the rim.

In testimony whereof I affix my signature in presence of two witnesses.

JAMES DONOVAN.
